(57) **CLAIM**

The ornamental design for “pressure sensor,” as shown and described.

DESCRIPTION

FIG. 1 is a front elevational view of a pressure sensor in accordance with the new design;

FIG. 2 is a side elevational view of the pressure sensor of FIG. 1;

FIG. 3 is a rear elevational view of the pressure sensor of FIG. 1;

FIG. 4 is a side elevational view of the pressure sensor of FIG. 1;

FIG. 5 is a top view of the pressure sensor of FIG. 1;

FIG. 6 is bottom view of the pressure sensor of FIG. 1; and,

FIG. 7 is a perspective view of the pressure sensor of FIG. 1.
